UNITED STATES PATENT OFFICE.

JAMES H. SAMMONS, ARTHUR C. HEADLEY, COOLIE J. EILAND, AND EUEL K. HEADLEY,
OF MYRTLEWOOD, ALABAMA.

LOG-TURNER.

1,245,387.

Specification of Letters Patent.

Patented Nov. 6, 1917.

Application filed April 4, 1917. Serial No. 159,832.

To all whom it may concern:

Be it known that we, JAMES H. SAMMONS, ARTHUR C. HEADLEY, COOLIE JOHN EILAND, and EUEL KENION HEADLEY, citizens of the 5 United States, residing at Myrtlewood, in the county of Marengo and State of Alabama, have invented certain new and useful Improvements in Log-Turners, of which the following is a specification, reference being 10 had to the accompanying drawings.

It is an object of the invention to provide a novel and improved device of this general character including skid knees having their outer or free ends provided with 15 penetrating members whereby a convenient and effective gripping action may be had with a log upon the carriage for properly turning said log.

The invention consists in the details of 20 construction and in the combination and arrangement of the several parts of our improved log turner whereby certain important advantages are attained and the device is rendered simpler, less expensive and otherwise 25 more convenient and advantageous for use, all as will be hereinafter more fully set forth.

The novel features of the invention will hereinafter be definitely claimed.

30 In order that our invention may be the better understood, we will now proceed to describe the same with reference to the accompanying drawings, wherein—

Figure 1 is a view in top plan illustrating 35 a log turner constructed in accordance with an embodiment of our invention; and

Fig. 2 is a transverse sectional view taken through the device as shown in Fig. 1 with the carriage in elevation.

40 As disclosed in the accompanying drawings, 1 denotes skids or log ways arranged in parallelism and which deliver upon the carriage C of a conventional type generally employed in saw mills. The discharging 45 end portions of the skids or ways 1 are provided in their upper faces with the recesses 2 adapted to receive the rounded portions 3 of the elongated arm or bar 4. The portions of the arm or bar 4 intermediate 50 the rounded portions 3 are angular in cross section and engaged with said angular portions 5 are the rocking members 6 having their outer ends rounded, as at 7, and extending outwardly from said rounded

edges 7 are the pins 8 adapted to penetrate 55 the log in order to materially facilitate the turning operation.

One end portion of the rod or bar 4 is extended and said extended portion is provided with an operating lever 9 whereby the 60 requisite rotation may be imparted to the rod or bar 4 for effecting the turning of a log. In turning a log the rod or bar 4 is so turned as to cause the outer or engaging end portions of the members 6 to move or 65 travel upwardly. The members 6 are automatically returned or moved in an opposite direction through the medium of the retractile members 10 herein disclosed as conventional coil springs operatively engaged with 70 the members 6 and with the cross piece 11 connecting the ways or skids 1.

From the foregoing description, it is thought to be obvious that a log turner constructed in accordance with our invention is of an extremely simple and comparatively inexpensive nature and is particularly well adapted for use by reason of the convenience and facility with which it may be assembled, and it will also be obvious 75 that our invention is susceptible of some change and modification without material departure from the principles and spirit thereof and for this reason we do not wish to be understood as limiting 80 ourselves to the precise arrangement and formation of the several parts herein shown in carrying out our invention in practice, except as hereinafter claimed.

We claim:

A log turner comprising, in combination, 90 log ways, a rod rotatably supported by said log ways, means for rotating the rod, rocking members carried by the rod, penetrating members carried by the outer ends of 95 the rocking members, and retractile springs engaged with the rocking members for normally maintaining the same in a lowered position.

In testimony whereof we hereunto affix our 100 signatures in the presence of two witnesses.

JAMES H. SAMMONS.
ARTHUR C. HEADLEY.
COOLIE J. EILAND.
EUEL K. HEADLEY.

Witnesses:

W. W. HUGHES,
E. A. Woods.
